C. A. Snow & Co.

UNITED STATES PATENT OFFICE.

AUSTIN M. COLLETT, OF OMAHA, NEBRASKA.

PINCH-BAR.

SPECIFICATION forming part of Letters Patent No. 480,398, dated August 9, 1892.

Application filed January 11, 1892. Serial No. 417,725. (No model.)

To all whom it may concern:

Be it known that I, AUSTIN M. COLLETT, a citizen of the United States, residing at Omaha, in the county of Douglas and State 5 of Nebraska, have invented a new and useful Pinch-Bar, of which the following is a specification.

This invention relates to pinch-bars; and it has for its object to provide an improvement 10 applicable to all ordinary lever pinch-bars and which is adapted to provide a heel or fulcrum-point which will effectually prevent the same from slipping when used to move cars, locomotives, or for any other purpose where 15 such bars have a tendency to slip.

It is also the object of this invention to provide a device which is cheap, simple, and effective, and which when applied to any bar will not decrease the value of the same for 20 any other purpose.

With these and many other objects in view, which will readily appear as the nature of the invention is fully understood, the same consists in the novel construction, combination, 25 and arrangement of parts hereinafter more fully described, illustrated, and claimed.

In the accompanying drawings, Figure 1 is a side elevation of a pinch-bar provided with my improvement in use. Fig. 2 is a perspective view of a pinch-bar provided with my 30 improvement.

Referring to the accompanying drawings, A represents a pinch-bar of ordinary construction and having the usual pinch end or point 35 B, that is adapted to contact with the rim of the wheel when moving cars or locomotives or with the other object to be moved. The said pinch-bar is provided in rear of said pinch-point with a threaded perforation C

or a series of such perforations, if desired, 40 which accommodate the heel or fulcrum-screw D. The screw D is constructed of hard steel and is provided with a conical bearing-point E, that is adapted to engage the rail and form a non-slipping heel or fulcrum-point for the 45 pinch-bar, and a squared head at its outer end adapted to receive a tool for adjusting the screw. It can be readily seen that while said set-screw serves the function of holding the pinch-bar to its work and effectually prevent- 50 ing the same from slipping when in operation at the same time the said set-screw can be set to obtain any desired leverage or adjusted to any-sized wheel or other object with which the same may be used.

The adaptations and advantages of the herein-described improvement in pinch-bars is thought to be apparent without farther description.

Having thus described my invention, what 60 I claim, and desire to secure by Letters Patent, is—

The combination, with a pinch-bar having a threaded perforation in rear of the pinch end thereof, of an adjustable fulcrum-screw 65 passed vertically through the perforation and provided at its upper end with a squared head and terminating below the bar in a conical heel or fulcrum-point, substantially as set forth.

In testimony that I claim the foregoing as my own I have hereto affixed my signature in the presence of two witnesses.

AUSTIN M. COLLETT.
